BOWLING GAME

Percival Urmy, Berkeley, Calif.

Application October 26, 1942, Serial No. 463,335

10 Claims. (Cl. 273—43)

My invention relates to improvements in a game mechanism.

The object of my invention is to provide a substantially automatic game mechanism which can be played by one or more persons without the need of anyone tending the machine. With this in mind my invention consists of various automatically controlled parts arranged to operate in ordered sequence to accomplish this purpose.

In the drawings, in which similar reference numerals refer to similar parts, I have shown one form in which my device may be embodied, although it is obvious that changes may be made in details and still be within the scope of the claims appended hereto.

In these drawings:

Fig. 1 is a general plan view of one embodiment of my invention;

Fig. 2 is a view in vertical elevation;

Fig. 3 is a view in perspective showing the relation of my device to an alley;

Fig. 4 is a sectional plan view of the setter, taken on the line IV—IV of Fig. 2 in the direction of the arrows;

Fig. 5 is a similar view of the playing table, taken on the line V—V of Fig. 2 in the direction of the arrows;

Fig. 6 is a partial view in vertical section of the conveyor side; and

Fig. 7 is a vertical cross-sectional view taken on the line VII—VII of Fig. 6;

Fig. 8 is a cross-sectional view of the gate taken on the same line as Fig. 7;

Fig. 9 is a vertical cross-sectional view of the playing table taken on the line IX—IX of Fig. 5; and

Fig. 10 is a similar view of the loading rack taken on the line X—X of Fig. 1.

Referring now to Figs. 1 and 2, there is shown in cross-section the principal parts in their operative relationship, one to the other. Of course, the size and detailed construction of any part may be varied, but these figures illustrate their general operative relationship.

The numeral 10 designates a playing floor or alley which may be of the size usually employed in bowling alleys, or may be the size of a miniature game such as is common now in amusement places. My invention is such that it lends itself to embodiment in large scale or small scale form.

In general, the rules followed in the playing of this game are those applicable to the game of bowling. In place of the usual pins I employ balls 11, which by suitable means are placed on playing table 12, from whence the player at

tempts to dislodge them with the play ball 13, which is impelled in the direction of the arrow 14. Alley 10 may be bordered by walls 10a, or by troughs.

5 In order to hold balls 11, of which there are usually ten, on playing table 12, shallow recesses or indentations 15 are provided. In the bottom of the indentations under the balls are holes 16, each with a pin 17 extending therein, and adapted, when table 12 drops, to lift out any balls 11 remaining therein. As shown in Fig. 9, pins 17 are carried by plate 17a mounted rigidly below table 12 so that the latter moves downward and upward in relation thereto. Pin 17 in the first recess is made hollow so that switch pin 18 may slide therein. When the head ball 11 is not in this first recess, pin 18 will project above the bottom of the recess about level with the surface of table 12. When in this position, pin 18 permits the upper contact 18a of switch 19 to open the circuit to solenoid 20 (see Fig. 2). When the circuit of switch 19 is thus open, solenoid 20 is de-energized and its armature 21 pivoted at 22 to playing table 12 falls, allowing the latter to drop into the dotted line position. The playing table is suitably hinged to alley 10 at 23 to permit this. The inclination of playing 12 when in this lower position is such that any balls remaining in the recesses 15 will be rolled out of them by pins 17 and down into trough 24, whence they will travel to the hopper 30 at the bottom of the lifting belt 25.

10 The spring tension on switch member 18a is such that pin 18 will move downwardly whenever a ball 11 is placed in the recess above it. This closes the circuit to solenoid 20, which holds the playing table 12 in its upper position almost on a level with alley floor 10.

Hand switch 26 with switch members 27, 28 is provided on the player's end of the device so that if at any time the player desires to remove balls 11 from the recesses in playing table 12, he may open the contact by depressing switch member 28, which de-energizes solenoid 20 and drops playing table 12.

15 The balance of the mechanism has to do primarily with the cycle of conducting the balls 11 from trough 24 and placing them in recesses 15 on playing table 12. Before describing this portion of the apparatus, I shall explain briefly the operation of the mechanism so far described.

The player usually employs two play balls 13 which are preferably larger than the playing pieces (balls) 11. If the first play ball thrown should knock head ball 11 from its recess, the

pressure on pin 18 will be released, switch 19 will open the circuit of solenoid 20, and playing table 12 will drop into its dotted line position and will empty all the balls, including play ball 13, into trough 24. This is considered a "strike." If the second play ball thrown should knock head ball 11 from its recess, with the described results ensuing, it would be considered a "spare."

If the first ball thrown does not dislodge head ball 11 from its recess, playing table 12 will remain in its upper position. If the second ball thrown likewise does not disengage head ball 11, but knocks other of the playing pieces 11 from their recesses, the score will be on the basis of the number of pieces knocked out of their recesses. The slight inclination of table 12 in its upper position will cause these balls to roll into trough 24. In order, then, to remove the balls remaining in recesses 15 on playing table 12, the player will press switch 26 to open the circuit of solenoid 20, and thus drop playing table 12 into its lower dotted line position, so the pins 17 can dislodge the remaining balls into trough 24.

I shall now describe the mechanism employed to take the balls from trough 24 and bring them into proper position in the ten recesses 15 on playing table 12.

Trough 24 empties the balls 11 and 13 into hopper 30, the floor of which is inclined toward the upright wall member 31 through which there is an opening 32 with an inclined floor. Lifting belt or conveyor 25 has ledges 33 set at less than a right-angle to the edges of the belt so as to cause balls 11 and 13 to rub against vertical wall 31 as they are being carried on the belt to the upper hopper 34 into which they fall from belt 25.

Adjacent each side of the opening 32 in vertical wall 31 are shutters or gates 35, 36, suitably interconnected by a shaft at 36a so that when one is moved upwardly the other moves upwardly. The normal position of these shutters (see Fig. 7) is such that shutter 35 closes the opening 32 and holds one ball in the recess and the next ball to it in the hopper is positioned so that shutter 36, when lifted, will hold the last-mentioned ball in the hopper (see Fig. 8). Thus, when shutter 35 is lifted to allow ball 11 in recess 32 to roll onto belt 25 and against ledge 33, shutter 36 will move upwardly and hold back the next ball so that only one ball at a time is emptied onto belt 25. When shutters 35 and 36 move downwardly, shutter 36 releases the ball it held and it moves into hole 32, and by the time it is in there, shutter 35 has closed off the end of opening 32 and holds the ball preparatory to the next opening of shutter 35. Shutters 35 and 36 are lifted by means of a lug 37 secured on the side of shutter 35. Lug 37 is engaged by ledge extension 33a after it rounds the lower tumbler 38 and these parts are so arranged that a ball 11 or 13 rolls out of opening 32 at the proper time to roll against ledge 33 and be carried up the full length of the conveyor, from whence it is discharged as belt 25 rolls over tumbler 39.

To prevent balls 11 and 13 from becoming wedged in hopper 30 so they will not flow into hole 32, I prefer to hinge hopper 30 at the end remote from hole 32 and by means of lug 36a on shutter 36 to impart a jiggling action to hopper 30. Fig. 8 shows the hopper lifted and Fig. 7 shows it dropped and in its normal position. This lifting and dropping each time gate 35 opens assures against any jamming of balls 11 and 13. Lifting belt 25 may be moved by any suitable and

convenient source of power. For example, I show the motor 80 with belt 81 driving tumbler 38. The motor circuit is controlled by switch 82 (see Fig. 2) which in turn is closed by foot 83 secured on the bottom of playing table 12. When the latter drops, foot 83 closes the motor circuit and belt 25 runs until the head ball 11 is deposited in its recess on playing table 12 and depresses switch pin 18 which lifts table 12 and opens the circuit to motor 80.

If desired, the motor 80 could run continuously.

As the balls fall one by one into hopper 34 when discharged from belt 25, they travel down inclined trough 40 and fall either into trough 41 or trough 42. The playing pieces 11 are preferably smaller in size than the play ball 13. Balls 11 fall from trough 40 into trough 41. Balls 13 fall into trough 42 through opening 43 in the bottom of trough 40 which is placed directly over the end of trough 41. Since hole 43 is smaller than balls 13, the latter will roll farther along trough 40 until they empty into trough 42.

As balls 11 fall into trough 41, they move into the ten recesses 44 in sliding rack 45 which lies directly above the perforated bottom of trough 41. The bottom of trough 41 has ten openings 47 which are arranged to be aligned with holes 44 in sliding rack 45 when it is desired to empty balls 11 from the rack. The normal position of rack 45 is such that the divisions 48 between each perforation 47 will lie across the bottom of recesses 44 and thus hold balls 11 in rack 45. When rack 45 is moved to the left, balls 11 will fall out of trough 41. A suitable spring 49 urges rack 45 to the right and in the position where it closes the bottoms of openings 44.

It is possible to control the sequence of discharge of balls 11 from trough 41 by varying the spacing of divisions 48 and holes 47. For example, I prefer that the ball which is to be the head ball shall precede the other balls in reaching its recess 15 on playing table 12. For this reason (see Fig. 10) the division 48 between the first and second perforations 47 is narrower than the divisions between any other two balls. It means that as rack 45 moves to the left the first ball will drop first because recess 44 will align with perforation 47 ahead of any other.

Lying directly beneath each perforation 47 in trough 41 is a tube 50 leading to one of the holes 51 in the ball setter 52. These holes 51 in setter 52 are in register with recesses 15 in playing table 12, so that when setter 52 drops to its lower position shown in dotted lines, balls 11 will be placed properly in the ten recesses 15.

Trough 42 which receives play balls 13 from trough 40 is hinged at 53 to upright wall 54. Its other end is suitably supported by a member 55 secured to trough 41. Thus, (see Fig. 2) as trough 41 drops to its dotted line position, trough 42 will move into its dotted line position and in doing so, will move below stop 56 and allow play balls 13 to empty into hinged trough 57. The latter is hinged at 57a to a rigid member supported from the floor or baseboard of the structure. Trough 57 has lower depending arm 58 adapted to engage the end of sliding rack 45. Trough 57 is sustained in the full line position by means of the weight 59 diagrammatically illustrated as acting through a line 60 and pulley 61.

Trough 41, rack 45, setter 52, and connecting tubes 50 may be arranged as an integral unit and suspended by means of weight 62 diagram-

matically shown as acting through lines 63 and 64 secured to the corners of setter 52. Weight 62 is calculated to support setter 52 and its attached parts in the full line position shown in the drawings until ten balls 11 have fallen into the rack 45 and the play balls 13 have fallen into trough 42 against stop 56. The weight of these dozen balls then overcomes weight 62 and setter 52 settles into the dotted line position over playing table 12. As setter 52 begins to settle onto table 12, a suitable mechanism is provided which will close the circuit of a hold-down device to assure that setter 52 remains in the dotted line position until the balls 11 are all deposited in recesses 15 in playing table 12. I have illustrated one form of mechanism to accomplish this, which comprises a cam member 65 secured to the bottom of setter 52 and adapted to engage bell crank armature 66 and to lift the latter so that its member 67 engages contact 68 and closes the circuit to hold-down solenoid 69 which acts on setter 52 through depending armature 70 suitably secured to 52 at 71. This hold-down circuit is maintained closed until balls 11 have been carefully deposited in recesses 15.

As setter 52 was settling into table 12, playing balls 13 rolled out of trough 42 as they came from behind stop 56. The weight of balls 13 with relation to weight 59 is such that they will move hinged trough 56 into the dotted line position and cause arm 58 to open rack 45. This discharges balls 11 from rack 45 and they pass down tubes 50 into recesses 15 on playing table 12. As balls 13 continue rolling down trough 57, they are fed into trough 57b, which leads the balls 13 back to the player.

Suitably arranged adjacent trough 57b is a switch mechanism 72 with its contacts normally closed. As balls 13 roll down trough 57b they engage projection 73 which opens the contacts of switch 72 and breaks the circuit to relay 74, thereby separating contacts 67, 68 and de-energizing hold-down solenoid 69. This allows the weight 62 to lift setter 52 away from playing table 12 into the full line position shown on the drawings. Thus, by means of switch 72 suitably placed in trough 57b to be contacted by balls 13 after balls 11 have had sufficient time to come to rest in recesses 15, I provide an automatic release of setter 52 and return of troughs 41, 42 and their associated parts to their raised position. The operation of the loading mechanism just described is such that as the balls 11 and play balls 13 are loaded into the rack 45 and trough 42 respectively, their weight overcomes weight 62 and lowers setter 52 onto playing table 12. This lowering movement releases balls 13 from trough 42 and their first movement while in trough 57 actuates rack 45 to release balls 11 so they pass down tubes 50 into recesses 15 on table 12. As balls 13 continue on their way toward the player, they engage switch member 73, which releases the positive hold-down means 69 and setter 52 is lifted by its weight 62 where it remains until the cycle is repeated.

What I claim is:

1. In an amusement apparatus the combination of a playing table, means for tilting said table, recesses on the surface of said table for receiving a plurality of balls, means movable toward and from said table for loading said balls thereon and means on said table for initiating the lifting of the same when said means is en-

gaged by a ball while it is still retained in said loading means.

2. In an automatic game device the combination of a playing table, loading and setting means suspended above said table adapted to hold a plurality of balls, means for lowering said last-named means adjacent said table, means for holding said setting means in its lowered position, means for releasing a playing ball while said setting means is being lowered, means actuated by said playing ball after its said release for opening said holding means to release the balls contained therein, and a second means actuated by said playing ball to release said setting holding means when said balls have been discharged onto the playing table.

3. In an automatic amusement device the combination of a playing table, a perforated trough having a rack therein, a setter, a hold-down mechanism therefor, a conveyor, a plurality of balls comprising playing pieces and playing balls, means for guiding said playing pieces into said rack, a hinged trough supported by said rack, means for conveying said playing balls into said trough, a counter-balance means which supports said rack and setter when empty, and which permits said rack and setter to lower itself when all of said balls are in place, a gate to release the playing balls in said trough when said rack and 30 setter are lowered, means actuated by said balls upon their release, which moves the rack in said perforated trough to drop the playing pieces to the playing table, and a second means actuated by said balls to release the hold-down on said 35 rack and setter.

4. In an amusement device the combination of a hinged playing table having a plurality of recesses each adapted to receive a ball, balls for said recesses, releasable means for supporting 40 said table, and means actuated by one of said balls when removed from its recess for controlling said release.

5. In an amusement device the combination of a tiltable playing table having a plurality of shallow recesses each adapted to receive a playing piece, electrical means for supporting said playing table, a source of electric energy, and a circuit control means actuated by one of said playing pieces to close said circuit and energize said 50 electrical means whenever said playing piece is in its recess.

6. In an amusement device the combination of a tiltable playing table having a plurality of recesses each adapted to receive a playing piece, a hole of less diameter than said playing pieces extending through said table adjacent each recess, means positioned beneath said playing table to project upwardly through said holes whenever said table assumes its tilted position, whereby 60 any playing pieces remaining in said recesses will be ejected therefrom.

7. In an amusement device the combination of a tiltable playing table, electrical means for supporting the same, a plurality of recesses in said table each adapted to receive a playing piece, one of said recesses having means to open and close the circuit to said electrical means, a setter carrying said playing pieces adapted to be lowered over said playing table and means on said setter for releasing the playing piece which is to be deposited in the last-named recess ahead of the release of the other playing pieces, whereby said electrical means will be energized and will lift 70 said table into its upper position substantially as

it receives the remaining playing pieces in their respective recesses.

8. In a game mechanism the combination of a setter having a plurality of spaced perforations, a perforated rack adapted to receive a plurality of playing pieces, means for carrying each playing piece to its respective perforation in said setter, perforated closure means having one of its perforations spaced in closer relation to a cooperating perforation in said rack than the others, whereby said perforation comes into alignment in advance of the other perforations to release one of said playing pieces in advance of the release of the others.

9. In a game mechanism the combination of a frame, means for mounting a setter in said frame, weighted counter-balances adapted to support said setter in a normally upward position, means for conducting a plurality of playing pieces into said setter, an electrically actuated holding means, means when said setter begins to settle due to the weight of said playing pieces overcoming said counter-balance, for closing the circuit to said holding means whereby said setter will be held in its lower position throughout said setting operation.

10. The combination of a tiltable playing table having a plurality of recesses therein each adapted to receive a playing piece, electrical means for lifting said table into playing position, circuit closing means actuated by one of said playing pieces for effecting operation of said electrical lifting means, an automatic playing piece setter mechanism adapted to be lowered into position adjacent said playing table to deposit said playing pieces and to be lifted therefrom after depositing said playing pieces, including a setter having perforations in alignment with the aforementioned recesses, a rack having a correspond-

ing number of perforations adapted to receive said playing pieces, a perforated member lying beneath said rack, each perforation in said member communicating with a corresponding perforation in said setter, said rack being movable to release the playing pieces so they drop into the perforations in said setter, a trough supported by said setter mechanism adapted to receive playing balls, trough means for conducting playing pieces and said playing balls into said rack and into said trough respectively, weight means for holding said setter mechanism in its upper position, the weight of said playing pieces and playing ball being calculated to over-balance said weight means and thereby lower said setter adjacent said playing table, a hinged trough in alignment with the trough supported by said setter mechanism and carrying said playing balls, means for releasing said playing balls into said hinged trough when said setter mechanism is lowered adjacent said playing table, the weight of said playing balls as they pass down said hinged trough actuating the rack in said setter mechanism, a trough for conveying said playing balls to the player's end of said machine, a conveyor mechanism for lifting said playing pieces and playing balls into the trough from which they are emptied into the rack and trough carried by the setter mechanism, motor driven means for operating said conveyor, a control circuit for said motor, means for closing said circuit when the playing table is in its tilted lowermost position, means for conveying said playing pieces and playing ball to said lifting conveyor, and means actuated by said lifting conveyor for admitting the playing balls and playing pieces thereonto one at a time.

PERCIVAL URMY.
